UNITED STATES PATENT OFFICE.

CHARLES H. SCHMIDT, OF ELIZABETH, NEW JERSEY, ASSIGNOR TO CHROME STEEL WORKS, OF CARTERET, NEW JERSEY, A CORPORATION OF NEW JERSEY.

ROTARY BALL-ROLLING MACHINE.

Application filed May 22, 1924. Serial No. 715,215.

To all whom it may concern:

Be it known that CHARLES H. SCHMIDT, a citizen of the United States, residing at Elizabeth, in the county of Union and State 5 of New Jersey, has invented certain new and useful Improvements in Rotary Ball-Rolling Machines, of which the following is a specification.

My invention relates to machines for 10 forging balls by passing heated rods or billets between grooved rolls and stationary shoes.

In machines of this type it is desirable at 15 times to substitute one shoe for another in order to change the passes. In machines as heretofore constructed, the shoes are arranged external to the rotating drum and a massive frame is required to support the shoes.

20 The object of my invention is to provide a compact machine and one in which the stationary shoes may be easily removed and which may be made in a plurality of sections. I accomplish these purposes by making the rotating member in the form of a cylindrical shell internally grooved while the stationary member is mounted within said shell upon a hollow drum keyed to the stationary shaft.

25 In the following description I shall refer to the accompanying drawings in which—

Figure 1 is a vertical sectional view of a machine embodying my invention.

Figures 2 and 3 are fragmentary sectional 30 views taken adjacent the intake and discharge openings of the machine respectively.

Figure 4 is a vertical longitudinal sectional view of the machine.

Figures 5, 6, 7, and 8 are sectional views 35 taken on the lines 5—5, 6—6, 7—7, and 8—8, respectively of Figure 1.

The internal stationary member consists of a hollow cylindrical drum 10, having its end walls keyed at 12 to the stationary 40 shaft 14, which is keyed at 15 in the end frame members 16. The upper portion of the drum is of smaller diameter than the lower portion, thereby forming a semi-cylindrical recess or seat for the shoes which 45 may be made up of a number of sections such as 18^a 18^b 18^c. These sections may be provided with end flanges which overhang the drum to which they are secured by bolts 19. The lower edges of the op-

posite sections are firmly supported by the 55 shoulders or ledges 21 in the drum.

The external rotating member consists of a shell each half of which is formed of a plurality of sections 25^a, 25^b and 25^c the two sets being separated by the inlet and 60 outlet openings 26^a and 26^b. As indicated in Figure 1 the sections of the internal fixed shoe are concentric with the shaft, but the two sets of outer shell sections are oppositely offset eccentric to the shaft so as 65 to form converging passes with the inner shoe as in ball rolling machines of this type. The sections of the outer rotary shell are bolted between end rings 27, 28, the rings 70 being provided with peripheral gear teeth by which they are geared to suitable driving means.

The stock-rods or billets 30 are fed into the inclined chute 32, the lowermost rod being held by the upturned edges of a series 75 of projecting spaced ledges 34. The rotary shell member is provided with projecting lips 35, rearward of the inlet and outer openings. These lips project into the path of the lowermost rod and as each moves 80 upwardly on the right hand side from the position shown in dotted lines to the position shown in solid lines in Figure 2, the lips pass between the ledges 34 and lift the lowermost rod, which rolls down into the 85 pass between the outer shell and the inner shoe as indicated in Figure 2.

As the outer shell rotates the rod 30 is first subjected to the shearing action of the ribs and the shaping and forging action of the grooves in the roughing pass of the inner and outer shoes 18^a and 25^a which may have a contour as indicated in Figure 6. This figure also shows the manner in which the metal displaced by the ribs is caused to flow inwardly into the deeper portions of the grooves. Since only the outer shoe travels while the inner shoe is stationary, the rod 90 will be carried around the circumference of the drum at half the speed of the revolving shell and consequently when the shell has made a half revolution so that the opening 26^a is at the position indicated at 26^b, the rod will be at the point indicated at 30^b 95 where it is being subjected to the shaping action of the intermediate pass shoes 18^b and 25^b. These may have a different configuration 100 from the roughing pass shoes, the 105

grooves being preferably somewhat flatter as indicated at Figure 7.

When the shell has made another half revolution so that the inlet opening 25^a is back to the position on the right hand side, the rod will have been completely transformed into a series of perfect spherical balls as indicated in Figure 8 and will be in the position indicated on the section line 8—8 of Figure 1, the balls then rolling out through the outlet 26^b. During the latter position of travel the balls traverse the narrow finishing pass between the finishing pass shoes 18^c and 25^e. Figure 3 shows the relative position of the inner and outer shoes just before the balls 30^d leave the finishing pass. At the next instant the outer shoe has moved so that the outlet opening 25^b is opposite the balls, that is, into the position indicated at 20 the left hand side of Figure 1.

I have traced the complete cycle of operations for the transformation of one rod into balls which requires one complete revolution of the outer shell. It will be evident, however, that each set of lips 35 picks up a rod as it passes the chute 32 so that a rod is picked up at every half revolution of the shell. I have shown the shell provided with two sets of shoes, but it is obvious that the 30 diameter of the inner drum and outer shell could be made large enough to permit the use of three or more sets of ball forming shoes.

I claim:

35 1. A ball rolling machine, comprising a rotatable cylindrical shell having a grooved

inner surface, and a stationary inner drum provided with grooves upon its outer surface which cooperate with said grooved inner surface of the rotary shell, said outer shell having openings for the insertion of the blank rods and for the discharge of the finished balls.

2. In a ball rolling machine as set forth in claim 1, the outer cylindrical shell being composed of a plurality of sections arranged in two oppositely off-set sets and end rings to which said sections are secured.

3. A ball rolling machine, comprising a rotatable cylindrical shell having a grooved inner surface, and a stationary inner drum having grooved shoes secured to its periphery, the grooves cooperating with said grooved inner surface of the rotary shell, said outer shell having openings for the insertion of the blank rods and for the discharge of the finished balls.

4. A ball rolling machine, comprising a rotatable cylindrical shell composed of a plurality of sections and end rings to which said sections are secured, and a stationary inner drum having a portion of its surface recessed, grooved shoes fitting within said recess and having their outer surfaces grooved to cooperate with the inner grooved surface of the rotary shell, said outer shell having openings for the insertion of the blank rods and for the discharge of the finished balls.

In testimony whereof I affix my signature.

CHARLES H. SCHMIDT.
